CLAIM

The ornamental design for a stacking crate, as shown and described.

DESCRIPTION

1.1 is a perspective view of a stacking crate showing my new design;

1.2 is a top plan view thereof;

1.3 is a perspective view thereof in a folded configuration;

1.4 is a front elevation view thereof;

1.5 is a right side elevation view thereof; and

1.6 is a perspective view thereof in which one side is opened.
